UNITED STATES PATENT OFFICE.

BENJAMIN BRISCOE, OF DETROIT, MICHIGAN, ASSIGNOR TO BRISCOE MANUFACTURING COMPANY, OF DETROIT, MICHIGAN, A CORPORATION OF MICHIGAN.

COOLER.

No. 810,030.

Specification of Letters Patent.

Patented Jan. 16, 1906.

Application filed September 28, 1903. Serial No. 174,921.

To all whom it may concern:

Be it known that I, BENJAMIN BRISCOE, a citizen of the United States, residing at Detroit, in the county of Wayne and State of Michigan, have invented certain new and useful Improvements in Coolers, of which the following is a specification, reference being had therein to the accompanying drawings.

10 The invention relates to coolers more especially designed for the dissipation of surplus heat from explosion-engines and of that type in which a fluid circulating medium is employed.

15 It is the object of the invention to obtain an inexpensive construction to manufacture and at the same time one which has great efficiency, especially under the varying conditions imposed in its use on motor-vehicles.

20 The invention consists in the construction and arrangement of the fluid-circulating conduits; further, in the construction of the radiating flanges used in connection with said conduits, and, further, in the peculiar construction, arrangement, and combination of parts, as hereinafter set forth.

25 In the drawings, Figure 1 is a cross-section through the cooler. Fig. 2 is a perspective view of some of the parts detached. Fig. 3 is a plan of the blank from which the radiating flange is formed, and Fig. 4 is an enlarged cross-section through said flange.

With my improved construction prior structures are greatly simplified by employing flattened liquid-conduits and forming the transverse air-conduits by peculiarly arranged wings or flanges.

35 As shown in the drawings, A and B are two headers arranged parallel to each other, and C designates flattened liquid-conduits extending between said headers and joined thereto. Each of the conduits C is preferably formed of a sheet-metal tube, which is flattened so that the parallel walls a and b are in close proximity. This tube may be formed from sheet metal, the blank having the opposite edges thereof seamed together at c, and the seam is preferably arranged centrally of the conduit, so as to form an inwardly-extending rib 40 which serves to space the walls a and b from each other. If desired, these walls may be further held spaced from each other by the arrangement of one or more intermediate

ridges d, formed in the sheet metal, as shown in Fig. 2.

55 Another advantage of the construction in the inwardly-projecting ribs or ridges is that in case of freezing the ribs afford an expansion for the conduit without danger of rupturing its walls or destroying the flanges, about to be described, which are sleeved thereon.

The conduits C are arranged in series parallel to each other and each is provided with radiating flanges, said flanges together serving to divide the space intermediate the conduits C into a multiple of transversely-extending air-conduits. Each of the flanges D is preferably formed from a sheet-metal blank e, which is slotted at f and is also bent upon the line g, so as to form oppositely-angling flanges h and i. The radiators thus formed may be sleeved upon the conduit C by passing the latter through the slits f, and by arranging said radiators with their flanges alternately angling in opposite direction triangular-shaped air-passages k will be produced on opposite sides of said conduit.

65 Each of the conduits C is preferably provided with a series of the radiating flanges D, 80 and the flanges of adjacent series preferably interlock with each other. To facilitate this engagement, one end of each flange is preferably flattened, as shown in Fig. 4, to form a tongue l, and this tongue is readily inserted 85 between the flanges of the adjacent series.

When all of the conduits C are provided with the flanges D, as described, the structure as a whole comprises a series of parallel flattened liquid-conduits and a series of transversely-extending air-conduits completely filling the space between the liquid-conduits. Thus when the cooler is arranged, as is usual on motor-vehicles, with the air-conduits extending longitudinally of the vehicle the air-circuit caused by the forward motion of the machine will be passed through the multiple of air-conduits, cooling the water-conduit C both by direct contact and by indirect contact through the medium of the flanges D.

90 In order that the cooler may be efficient when the vehicle is at rest as well as when in motion, the flanges D are preferably perforated, as at m. These perforations permit of a circulation of air through the cooler in a 95 transverse direction to the air-passages k or

in substantially the same direction as the circulation of the fluid in the conduit C. As a consequence, if the air is in motion in any direction a circulation will be permitted 5 through the cooler, or a circulation will be induced merely by the heating of the air.

What I claim as my invention is—

1. In a cooler, a liquid-conduit comprising a flattened tube having the parallel walls 10 thereof in close proximity, and an inwardly-extending rib on said tube for holding said parallel walls spaced from each other, and a radiating flange sleeved upon said tube.
2. In a cooler, the combination of a liquid- 15 conduit formed of a flattened tube having parallel walls thereof in close proximity, and an inwardly-extending rib on said tube formed by seaming the adjoining ends of said tube, for holding said parallel walls spaced 20 from each other.
3. In a cooler, the combination with a flattened liquid-conduit of a radiating flange therefor, formed of sheet metal struck up to form oppositely-angled flanges, and slitted 25 at the angle to be sleeved on said conduit.
4. In a cooler the combination with a flattened liquid-conduit of a plurality of radiating flanges therefor, each comprising a sheet-metal blank struck up to form oppositely- 30 angled flanges, and slitted to be sleeved on said conduit, said flanges being arranged in series on said conduit, alternately oppositely inclined to form transversely-extending air-passages and being apertured for air circulation, transverse to said passages. 35
5. In a cooler the combination of a plurality of parallel flattened liquid-conduits, and a series of radiating flanges on each conduit, formed from sheet metal, and struck up to

form oppositely-angled flanges, and slitted at 40 the angle to be sleeved on said conduits, said flanges being alternately arranged so that together they form diamond-shaped conduits with the flanges in one series inserted between adjacent flanges in the parallel series. 45

6. In a cooler, the combination with a plurality of fluid-conduits, of separately-formed flanges projecting therefrom and arranged at oppositely-disposed angles, the flanges on adjacent tubes interlocking. 50

7. In a cooler, the combination with a conduit, of a radiating flange therefor, struck up to form oppositely-angled flanges, and apertured through the angle portion to be sleeved on said conduit. 55

8. In a cooler, a series of liquid-conduits and oppositely-disposed radiating flanges arranged in criss-cross fashion in the space between the conduits to form a series of closely-associated air-passages therebetween, said 60 flanges being apertured for the reception of said conduits.

9. In a cooler, the combination of a liquid-conduit comprising a flattened tube having parallel walls in close proximity and a radiating flange sleeved upon said tube of an inwardly-extending bead or corrugation in the wall of said tube, the said bead or corrugation constituting a means for holding the parallel walls spaced from each other and affording a means of expansion for said conduit in 70 case of freezing.

In testimony whereof I affix my signature in presence of two witnesses.

BENJAMIN BRISCOE.
